OSCILLOGRAPH SWEEP CIRCUIT

Harold J. Schrader, Haddonfield, and Ronald D. Scheldorf, Haddon Heights, N. J., assignors to Radio Corporation of America, a corporation of Delaware

Application February 20, 1942, Serial No. 431,626

14 Claims. (Cl. 171—95)

This invention relates generally to cathode ray oscilloscopes and particularly to sweep circuits for cathode ray oscilloscopes in which a source of electric phenomena to be observed is caused to produce instantaneously a single timing voltage to provide a single traversal of the fluorescent screen by the cathode ray.

More particularly, the invention relates to a circuit and method for producing such a single timing voltage substantially instantaneously with the application of the initial portion of the electric phenomena to be observed, and of duration and rate dependent on the time constant of the circuit.

Other methods and circuits for producing single timing pulses have been used heretofore, but they have been characterized generally by considerable time delay between the application of the starting potential and the beginning of the timing pulse.

This invention therefore has great utility over other systems when the measurement of signals of short duration or transients is required. In all such systems the transient is often used to start the timing pulse. It is obvious that any time delay between the start of the transient and the start of the timing pulse, both measured at the oscilloscope, would prevent any useful indication of the transient during this interval.

Another problem in measuring transient voltages is caused by their customarily short duration. This necessitates an extremely rapid traversal of the screen by the cathode ray with necessarily a low amount of light energy available to the observer, resulting in poor visibility, because the cathode ray intensity must be limited during absence of scanning signal to prevent burning of the fluorescent screen. This invention provides means for increasing the intensity of the cathode ray only during the time interval of the single timing pulse which is in turn under control of the transient voltage under measurement. This arrangement permits greatly increased illumination of the fluorescent screen during the scanning interval and at the same time permits low normal cathode ray intensity to prevent burning of the screen.

An object of the invention is to provide means for producing a single timing pulse for cathode ray oscilloscope scanning which is started in response to an initial portion of the signal under measurement and the duration or rate of which is controlled by the time constant of an associated circuit.

Another object of the invention is to provide a circuit or method for producing a single timing pulse for use in cathode ray oscilloscope measurements of transients, in which the beginning of the transient substantially instantly starts the timing pulse and at the same time causes an in-

crease in the intensity of the cathode ray for the duration of the timing pulse.

Still another object is to provide means for producing a single non-oscillatory timing pulse for oscilloscope use, in response to an initial portion of a starting signal or a transient of a selected polarity wherein the rate or duration of the pulse is determined by the time constant of the pulse circuit. An additional object is to provide manual switching means for reconditioning the circuit after each actuation by the starting potential.

In describing the invention, reference will be made to the drawing, which shows a schematic diagram of one embodiment of the system.

Referring to the drawing, the wave form shown at the extreme left is that of a typical transient or starting signal under measurement. This signal is applied to the vertical deflecting element 11 of the conventional oscilloscope 12 and to the input 13 of wide band amplifier tube T₁. The output of tube T₁ is coupled in any conventional manner to the input of the conventional phase inverter circuit containing tube T₂. The single-pole double-throw switch S₁ provides signals of either polarity to the cathode of diode rectifier T₃ by utilizing either the input or output of phase inverter tube T₂ as desired.

The anode of the diode T₃ establishes and applies a voltage of only one polarity to the grid of tube T₄ of the trigger circuit comprised of the tubes T₄ and T₅. It will be seen that the position of switch S₁ controls the starting polarity of the transient signal.

When a signal is applied to the input circuit of tube T₁ the diode tube T₃ will conduct on each negative cycle. The position of the switch S₁ is determined by the polarity of the input signal. The value of the variable resistor R₂ varies the bias, and determines the voltage at which the diode T₃ will conduct. When sufficient signal voltage is applied to the diode T₃, it becomes conducting and the voltage developed across the variable resistor R₂ causes trigger tube T₄ to become non-conducting because of the resultant high negative grid bias applied. The value of resistance of R₂ determines the sensitivity of the trigger circuit. When tube T₄ becomes non-conducting, tube T₅ becomes conducting. With tube T₅ conducting, the grid potential of tube T₄ is made even more negative to maintain the cut-off condition. This in turn increases the bias on the diode tube T₃ so that it becomes non-conducting except for much higher signal voltage than is required to first actuate it. When tube T₅ is conducting, the bias of the D.-C. amplifier tube T₆ is decreased, causing the anode current to increase. The increase of anode-cathode current in tube T₆ causes the voltage across the resistor

18 to rise, which raises the potential of the cathode of the diode tube T_7 .

The anode potential of diode T_7 rises, to offset the rise in its cathode potential, at a rate determined by the time constant of resistor R_1 and capacitor C_1 in the anode circuit of the diode.

The amplitude of the pulse developed across the capacitor C_1 is determined by the static characteristic of the diode tube T_7 . Although the substitution of a triode, having sharp cut-off characteristics, would be desirable from the standpoints of sensitivity and gain, the diode has been found to be preferable because of its inherently sharper cut-off features. The diode circuit, comprising tube T_7 and the time delay circuit R_1 , C_1 , can, for special purposes, be caused to produce a train of pulses similar to the single pulse described heretofore, by driving the diode with voltage pulses of square wave form from a conventional square wave generator 20 connected across the resistor 18 through the switch 21. The individual pulses of the train would be limited in amplitude by the cut-off characteristics of the diode and of rate or duration determined by the time constant of the diode anode circuit. The amplifier tube T_8 is driven by the voltage developed across capacitor C_1 . Output for use on the horizontal deflecting element 14 of the cathode ray oscilloscope 12 is taken between a point 15 on resistor 16 and ground.

A typical timing pulse developed by the circuit is shown at the extreme right side of the drawing. It is apparent that the pulse starts as soon as the driving signal reaches a predetermined potential the polarity of which is controlled by the position of the switch S_1 and the amplitude by the values of the variable resistors R_2 and R_3 . The pulse will then continue to rise for an interval determined by the time constant of the circuit comprised of resistor R_1 and capacitor C_1 , after which it will remain at maximum potential determined by the normal potential across resistor 16.

In order to recondition the circuit for actuation by a subsequent transient or starting signal, a reset switch S_2 is connected between the grid of trigger tube T_5 and ground. Temporary closing of this switch, which is normally open, shorts the grid circuit of tube T_5 , restores tubes T_3 , T_4 , and T_5 to normal operation, and causes the cathode trace to return to its original position. Voltage for increasing the intensity of the cathode ray during the operation interval of the circuit, to provide increased illumination, is derived from the anode circuit of tube T_4 and applied to the control grid 17 of the oscilloscope 12. Similar control voltage could be obtained from other suitable points in the circuit.

We claim as our invention:

1. In a cathode ray oscilloscope circuit for observing transient voltages, means for producing in said circuit a single timing voltage pulse in response to an initial portion of said transient voltages, a time constant circuit, means for deriving from said time constant circuit a timing voltage pulse for said transient, and manually operable means for reconditioning said circuit after each application of said transient voltages.

2. In a cathode ray oscilloscope circuit for observing transient voltages, means for producing in said circuit a single non-oscillatory timing voltage pulse in response to an initial portion of said transient voltages, a time constant circuit, means for deriving from said time constant cir-

5 cuit a timing voltage pulse for said transient, and manually operated means for reconditioning said circuit after each application of said transient voltage.

3. In a cathode ray oscilloscope circuit for observing transient voltages having means for producing a single timing voltage pulse in response to an initial portion of said transient voltages and of duration determined by the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse and means for impressing said timing pulse on a deflecting element of said cathode ray oscilloscope.

4. In a cathode ray oscilloscope circuit for observing transient voltages having means for producing a single timing voltage pulse in response to an initial portion of said transient voltages and of duration determined by the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse and means for impressing said timing pulse on a deflecting element of said cathode ray oscilloscope.

5. In a cathode ray oscilloscope circuit for observing transient voltages having means for producing a single non-oscillatory timing voltage pulse in response to an initial portion of said transient voltages and of duration determined by the time constant of the circuit, a triode actuated by said transient voltages, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, and means for impressing said timing pulse on a deflecting element of said cathode ray oscilloscope.

6. In a cathode ray oscilloscope circuit for observing transient voltages having means for producing a single non-oscillatory timing voltage pulse in response to an initial portion of said transient voltages and of duration determined by the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, and means for impressing said timing pulse on a de-

flecting element of said cathode ray oscilloscope, and means for controlling the intensity of the cathode ray in said oscilloscope by voltages derived from said timing pulse circuit.

7. In a circuit for producing a single pulse of predetermined duration, a source of starting potential, a polarized trigger circuit comprising a diode having a cathode and anode, a first triode having a cathode, a control electrode and an anode, a second triode having a cathode, a control electrode and an anode, a connection from the anode of said diode to the control electrode of said first triode, a resistor from said control electrode of said first triode to the anode of said second triode, a resistor from the anode of said first triode to the control electrode of said second triode, means for providing control electrode and anode potentials to each of said triodes, a circuit for applying the starting potential to the cathode of said diode, means connecting the control electrode of said second triode to the cathode of a second diode, a time delay circuit in the anode circuit of said second diode, and means for utilizing pulses developed across said second diode.

8. In a cathode ray oscilloscope circuit for measuring transient voltages, means for producing a single timing voltage pulse in response to an initial portion of said transient voltages and of duration determined by the time constant of the circuit, comprising, in combination, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, means for impressing said timing pulse on a deflecting element of said cathode ray oscilloscope, and manually operable means for reconditioning said circuit after each application of said transient voltages.

9. In a cathode ray oscilloscope circuit for observing transient voltages having means for producing a single timing voltage pulse in response to an initial portion of said transient voltages and of duration determined by the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, means for impressing said timing pulse on a deflecting element of said cathode ray oscilloscope, means for controlling the intensity of the cathode ray in said oscilloscope by voltages derived from said timing pulse circuit, and manually operable means for reconditioning said circuit after each application of said transient voltages.

10. In a cathode ray oscilloscope circuit for observing transient voltages having means for producing a single non-oscillatory timing voltage pulse in response to an initial portion of said transient voltages and of duration determined by

the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, means for impressing said timing pulse on a deflecting element of said cathode ray oscilloscope, and manually operable means for reconditioning said circuit after each application of said transient voltages.

11. In a cathode ray oscilloscope circuit for observing transient voltages having means for producing a single non-oscillatory timing voltage pulse in response to an initial portion of said transient voltages and of duration determined by the time constant of the circuit, a triode actuated by said transient voltage, a phase inverter in the output circuit of said triode, a diode selectively connected between the output of either said triode or said phase inverter and the input of a polarized trigger circuit, a D. C. amplifier between the output of said trigger circuit and the cathode of a second diode, a time constant circuit in the anode circuit of said second diode for determining the rate of said single timing pulse, means for impressing said timing pulse on a deflecting element of said cathode ray oscilloscope, means for controlling the intensity of the cathode ray in said oscilloscope by voltages derived from said timing pulse circuit, and manually operable means for reconditioning said circuit after each application of said transient voltages.

12. In a circuit for producing a single pulse of predetermined duration, a source of starting potential, means for producing said pulse in response to an initial portion of said starting potential and of duration determined by the time constant of the circuit, and manually operable means for reconditioning said circuit after each application of said starting potential.

13. In a circuit for producing a single non-oscillatory pulse of predetermined duration, a source of starting potential, means for producing said pulse in response to an initial portion of said starting potential and of duration determined by the time constant of the circuit, and manually operable means for reconditioning said circuit after each application of said starting potential.

14. An oscilloscope deflection circuit for producing a single sweep deflection potential in response to a transient phenomenon comprising a non-oscillatory control impulse generating device responsive to the initial part of the transient phenomenon for generating a single control impulse, means including a time constant circuit for producing a substantially constant rate of change of potential in a predetermined polarity direction in response to the generated control impulse, and means to reset the control impulse generating means and to produce a change of potential in the opposite polarity direction in order that the circuit may be rendered responsive to the next succeeding transient phenomenon.
